UNITED STATES PATENT OFFICE.

ALFRED LEHNER, OF KELSTERBACH, GERMANY, ASSIGNOR, BY MESNE ASSIGNMENTS,
TO EASTMAN KODAK COMPANY, OF ROCHESTER, NEW YORK, A CORPORATION OF
NEW YORK.

MANUFACTURE OF POLYCHROMIC SURFACES.

1,112,541.

Specification of Letters Patent.

Patented Oct. 6, 1914.

Application filed February 15, 1909. Serial No. 478,037.

To all whom it may concern:.

Be it known that I, Dr. ALFRED LEHNER, citizen of Switzerland, residing at Kelsterbach-on-the-Main, Germany, have invented 5 certain new and useful Improvements in the Manufacture of Polychromic Surfaces; and I do hereby declare the following to be a full, clear, and exact description of the invention, such as will enable others skilled in 10 the art to which it appertains to make and use the same.

This invention relates to the manufacture of polychromic surfaces, that is to say surfaces having designs or legends formed 15 thereon in different colors. Sheets marked with such multicolor designs are employed for various purposes in the arts. For example they may serve as decorative veneers to be applied to different articles of personal 20 wear for example or they may be made as multicolor hatched screens for color photography. Hitherto no method has been known, whereby transparent multicolor designs could be produced by taking a surface, 25 a portion of which was provided with a design in one color and coloring the remaining portions of such surface with a solution of another color, without first protecting the first portion of the design with a resist. 30 This use of resists or stencils, while possible where the masses of color applied are large, becomes more difficult as such masses become smaller and finally, when the colors are to be distributed in minute sections or strips, the 35 method of stencils becomes impracticable, since an accurate register or stopping out is impossible. Other methods of covering the already colored portions with resists are, under such circumstances, so tedious that 40 they are too costly to be employed and it is hence desirable to devise means for avoiding the same. This has been accomplished by the present invention which permits the uncolored portions of a surface already provided 45 partially with a colored design to be colored with a different color, speedily and perfectly and without the employment of resists or stencils.

In the drawings, in which I have illustrated one method of carrying out my invention, Figure 1 is an enlarged cross-sectional view of a portion of a sheet of material prepared for the formation of a polychromic screen used in photography; Figs. 2

and 3 are plan views of the screen, showing 55 different stages of making, as hereinafter described; and Fig. 4 is a similar view of the complete screen.

My invention is based on the following discovery which I have made. If a sheet or 60 surface which has been colored in part with a dye or color solution, is dried and then immersed in a dye-solution of another color the uncolored portion will thereby be colored with sufficient intensity while the already 65 colored portion will not receive any of the color of this dye solution, if the time of immersion is sufficiently short. If, for example, a sheet of celluloid is partly dipped into a concentrated red alcoholic dye bath. 70 such as a solution of rhodamin and then rinsed in water to remove excess of dye adhering to the same and then allowed to dry, a sheet colored intensely red on a portion of its surface is obtained. If thereupon this 75 sheet is entirely immersed for a few seconds only in a second alcoholic green dye bath and then immediately dipped into water to check the action of the latter solution at once, the portion of the surface not dyed 80 red will be found to be colored intensely green while the red portion of the surface has remained unchanged.

In dealing with sheets or surfaces of gelatin, casein, or the like instead of alcoholic 85 dye baths aqueous dye baths are employed and the surface or sheet is dipped into alcohol or wiped off or freed from the excess of dye by pressing an absorbent sheet thereon or such excess of color may be removed by 90 suction. In other respects the process is the same as for the treatment of celluloid.

As an example of practically carrying out this process let it be proposed to provide a sheet or film of celluloid with a red background, green transparent letters and blue initials. The desired legend is printed thereon with printers' ink and the sheet is then immersed entirely into a red alcoholic dye bath, such as a solution of rhodamin in 100 alcohol. Thereby the background is dyed red, the letters remaining undyed. After drying, the printers' ink of the small letters is removed and the sheet is then dipped for about two seconds into a concentrated alco- 105 holic solution of malachite green and then immediately immersed into water. Thereby the small letters are dyed green, the red

background remaining unchanged, the initials being protected against the color by the printers' ink. After drying, the printers' ink is now removed from the initials and the sheet is next immersed for about one 6 second into a concentrated alcoholic blue dye solution such as spirit blue and immediately brought into a stream of flowing water. By this treatment the initials are dyed blue, while the red and green portions of the surface do not take any further color. To 10 prevent the back of the sheet from receiving any color, it may be coated with a resist such as printers' ink.

15 Another example embodying my invention is the preparation of multi-color screens for color photography. If it be desired to prepare a two-color screen, using celluloid as the screen-sheet, for example, I print or otherwise produce on such sheet a fine system of 20 parallel lines, with printers' ink or other resist and then immerse the sheet entirely in an alcoholic color bath whereby only the unprinted portion of the surface, that is, the intervals between the lines, is colored.

25 After drying the sheet, the printers' ink or other resist is removed for example with oil of turpentine, thus exposing the undyed portion. The sheet is then immersed into a 30 second alcoholic dye-solution of another color for a very short time and then immediately dipped into water, all as in the first example, whereby the lines not dyed in the first step are now dyed with the second color. 35 A two-color screen is thereby produced.

For producing three-color screens I combine the method just described with that set forth and claimed in my application, Serial No. 478,036.

40 In detail, the manner of proceeding is illustrated in the drawings and described in the following example, when making a parallel hatched screen. A system of fine parallel lines in intaglio is formed on the surface of a sheet of transparent celluloid X 45 as in Fig. 1 by placing the same upon a metallic dye having the requisite hatching formed thereon in relief and pressing the two into intimate contact with each other 50 and heating the celluloid or the dye, or both at the same time. The intaglio lines thus formed should be so distributed and of such an area as to take up one-third of the entire surface of the sheet. The relief portion of 55 the surface so hatched and the back, if desired, are then coated with a color or dye resist Y by inking the same with printers' 60 ink with the aid of an inking roller, for example. Thereby the sheet will take color only on the intaglio hatching. It is now immersed in a blue alcoholic dye or color bath. Thereby the intaglio lines alone are colored blue, as indicated by a, Fig. 2.

The sheet is removed from the bath after 65 the intaglio hatching has been sufficiently

colored; the sheet is then washed and the printers' ink Y is removed therefrom. Thereupon a second system of parallel intaglio lines crossing the first system is impressed in the same surface of the sheet in the manner above set forth and the sheet is again inked in as before. It is now immersed in an alcoholic green dye bath such as a solution of malachite green. At this point the process differs essentially from the process 70 set forth in my aforesaid application in that, while in the latter, the length of immersion was of no special importance the element of time plays an all-important part under this invention, the time of immersion being under the same limited to a minimum, depending on the nature the strength of the dye bath, the depth of color of the lines, etc. In general however the sheet will be left in the bath only a few seconds. The sheet is allowed to remain in this bath only about three 75 seconds. On withdrawing the same it will be found that only the uncolored parts of the intaglio lines, have received the green color, as shown at b Fig. 3, while the parts 80 crossed by the previously colored blue lines have taken no further color. The sheet is then washed and dried as before. Thereupon the printers' ink is removed from the hatched surface the ink on the back being 85 allowed to remain and the sheet having no resist on the hatched surface is dipped into a third bath viz. a red alcoholic dye bath such as a rhodamin solution and allowed to remain therein only about one second. By 90 this last step the uncolored last third of the hatched surface of the sheet is colored intensely red, as indicated at c, Fig. 4, the remaining portions of the surface remaining 95 unaffected by said red color.

100 It has been found that, notwithstanding the short period during which the last two color baths have been allowed to act on the sheet, the colors taken by the same are of sufficient intensity for the purposes of color photography. The sheet is finally pressed between two flat surfaces while applying heat, whereby the several colored portions are brought into one plane. A color screen 105 in which the different colors are all lodged 110 in the celluloid is thus obtained.

115 It will be seen from the foregoing that my invention essentially resides in the fact that the plate or surface after having been printed or otherwise marked on a portion of 120 its surface with a dye or color bath of one sort, is thereupon, after drying, immersed into a color bath or dye of the same sort but of a different color and that thereby the interaction between resisting colors or fatty 125 colors and aqueous or fat-repelling colors is essentially avoided.

130 From the above it will be seen that an important part of my invention is based on the discovery made by me that if a sheet or

surface of material used for making poly-chromic surfaces, such as celluloid, gelatin, casein or the like, which has been printed or otherwise marked with a design or color 5 comprising a certain vehicle or menstruum or if the said surface after the color has dried thereon be dipped or immersed in a solution or bath of another color comprising the same vehicle or menstruum for a short period of 10 time, the remaining uncolored portion of the surface will be colored with the second color while the already colored portion will not receive such second color, although the said first color portion of the design is not 15 masked or protected against such action with a resist. I have found that in most cases such immersion in the second color bath should not exceed a few seconds, the necessary minimum time depending on the 20 strength and nature of the dye bath.

What I claim and desire to secure by Letters Patent is:

1. A process for making multicolored surfaces consisting in dyeing portions of the 25 surface and drying, then allowing a dye in substantially the same menstruum as that of the first to act so briefly on the uncolored surfaces as to color them only and not to affect those areas previously dyed.

2. A process of forming multicolored objects which consists in coloring a portion of an object with one color, then immersing the object into a bath of another color comprising 35 substantially the same menstruum as employed for applying the first color for a period of time only sufficient to color the remainder of the surface without affecting the color first applied.

3. The process of forming multicolored 40 objects, which consists in coloring a portion of the surface of an object with one color and after drying immersing the entire object into a bath of another color comprising substantially the same menstruum as employed for applying the first color for a time 45 just sufficient to color the remainder of the surface without affecting the color previously applied.

4. The process which consists in applying 50 a color bath to the entire surface of a dry body, already colored with a color mixture of another color employing substantially the same menstruum as the said color bath on a portion of its surface for a time only 55 sufficient to color the remainder of the surface and without affecting the color first applied.

5. The process of coloring sheets, which 60 consists in marking a design on the surface of such sheets with a resist, immersing the

sheet in a color bath, then removing and drying the sheet, then removing the resist and again immersing the sheet into a bath of another color for a time only sufficient to color the newly exposed portions of the surface. 65

6. The process of coloring sheets which consists in immersing a sheet colored on a portion of its surface with one color and covered with a resist on a portion only of 70 the remainder of such surface, into a bath of another color but comprising substantially the same menstruum as used in applying the first color, for a time only sufficient to color the uncolored exposed portion and 75 without affecting the colors previously applied.

7. The process of making color-screens which consists in immersing a dry color hatched sheet into a bath of another color 80 but comprising substantially the same menstruum as employed in applying the previous colors, for a time sufficient only to color the uncolored remainder of the surface of the sheet, and without affecting the colors 85 previously applied.

8. The process of making color screens which consists in hatching a sheet with intaglio parallel lines and coating all of the surface thereof with the exception of the intaglio lines with a resist and then immersing the sheet into a color bath then drying the sheet and removing the resist and applying to the same another series of intaglio lines, crossing the first series and again covering 95 the entire surface, with the exception of the intaglio portions, with a resist, and immersing the sheet into another color bath for a time only sufficient to color the uncolored exposed intaglio portions, then again drying, then removing the resist from the front surface and then immersing the sheet into a third color bath for a time sufficient only to color the uncolored portion. 100

9. The process which consists in coloring 105 a portion of the surface of an object with one color, then washing with a liquid differing from the menstruum of the color, then submitting the entire surface of the object to the action of a bath of a different color 110 comprising substantially the same menstruum as that of the first color for a time only sufficient to dye the uncolored portions without affecting the dye first applied.

In testimony whereof I hereunto affix my 115 signature in the presence of two witnesses.

DR. ALFRED LEHNER.
